FEED MECHANISM

Eugene Martin, Wesleyville, Pa., assignor to Read Standard Corporation, a corporation of Delaware

Application December 21, 1949, Serial No. 134,321

4 Claims. (Cl. 214—17)

1

This invention relates to improvements in apparatus for feeding granular or finely divided solid material from a hopper or other source to a receiver wherein a pressure differential exists between the hopper and the receiver.

One form of such device, disclosed in my application Serial No. 48,462, filed September 9, 1948, embodies a pair of feed valves movably supported within a valve body having an upper feed inlet and a lower feed outlet. The feed valves are operatively connected to means disposed within the body for alternately moving them to and away from respective vertically spaced valve seats extending inwardly of the inner wall of the valve body and defining a feeding chamber between them. Valve controlled means is provided for pressurizing the feed chamber while the upper and lower feed valves are closed in order to facilitate opening of the lower feed valve against the pressure in the receiver and to facilitate discharge of the material from the feed chamber into the receiver. Valve controlled means is also provided for venting the pressure in the feed chamber after the lower feed valve re-closes and before the upper feed valve opens, in order to prevent blow back of pressure into the feed hopper. Sequential timing means automatically controls the proper operating sequence of the feed valves, the pressurizing valve and the vent valve. In the said application there is disclosed operating means within the valve body for opening and closing the feed valves including cylinders and hydraulically operated pistons disposed therein.

An object of the present invention is to provide in a feeding apparatus of the type described, improved hydraulic operating means that permits employing larger cylinders without increasing the overall size of the feeder, whereby less fluid pressure is required for operation of the feed valves.

Another object of the invention is to provide an improved construction and arrangement of the lower feed valve and the cylindrical housing that supports the feed valve and encloses the operating means for the valve to facilitate opening of the lower feed valve against the pressure existing in the pressurized receiver.

Still another object of the invention is to provide an improved compactly arranged feeding device of the type described that is simple in construction, efficient in operation and embodies improved and compactly arranged means for controlling the sequential operation of the material feed valves, the chamber pressurizing valve and the chamber vent valve.

2

Other objects and advantages of the invention residing in the construction and combination of parts will become apparent from the following description when read in connection with the accompanying drawings disclosing a preferred embodiment of the invention.

In the drawings, Figure 1 is a vertical central sectional view through the novel feed device with parts shown in elevation;

Figure 2 is a sectional view taken on the line 2—2 of Figure 1;

Figure 3 is a sectional view taken on the line 3—3 of Figure 1;

Figure 4 is an enlarged fragmentary sectional view taken on the line 4—4 of Figure 2 showing the feed valves, the actuating means therefore and the housing supporting the feed valves and housing the actuating means, the feed valves being shown in their seated position;

Figure 5 is a sectional view taken on the line 5—5 of Figure 2 with the upper feed valve shown in its open position;

Figure 6 is a sectional view taken on the line 6—6 of Figure 2 with the lower feed valve shown in its open position;

Figure 7 is a fragmentary sectional view of one of the ball check valves in the cylinder heads of the valve actuating means;

Figure 8 is a view in elevation of the invention showing the arrangement of the pressure fluid distributing valves, the pressurizing valve and the vent valve on the body of the feed mechanism, with parts in section to show the cam shaft and cams for actuating the valves;

Figure 9 is an enlarged fragmentary sectional view taken on the line 9—9 of Figure 2 of the pressurizing valve;

Figure 10 is an enlarged fragmentary sectional view taken on the line 10—10 of Figure 2 of the vent valve; and

Figure 11 is a diagrammatic view of the cams showing their relative positions.

The invention is hereinafter described with reference to the feeding of finely divided coal into a pressurized receiver, however, it will be evident that it may be employed for feeding various kinds of granular or finely divided solid materials.

Referring to the drawings, particularly Figure 1, the feeding device comprises a preferably cylindrical valve body 10 open at the top and bottom. The upper end of the valve body 10 communicates with a coal supply hopper 11 and the lower end thereof communicates with a pressurized tank or receptacle 12. Operating mechanism located outside the valve body 10,

3 and the valve body itself, are preferably enclosed by a housing 13 attached in suitable manner to the valve body 10.

Considered from top to bottom, the wall of the valve body 10 tapers to form an internal annular ledge 14, then expands abruptly and tapers again to form a second internal annular ledge 15, and then expands again for its remaining distance, to define within the body a coal receiving chamber 16, a pressurizing chamber 17, and a discharge mouth 18. An annular valve seat 19 is detachably secured in any suitable manner, as by bolts 20, to the upper annular ledge 14, and is provided with a non-metallic yieldable seat ring 21. The seat ring 21 is firmly secured to the valve seat 19 by bonding or other suitable means. In similar manner, an annular valve seat 22 provided with the non-metallic seat ring 23 is detachably secured to the lower annular ledge 15 by bolts 24.

Disposed in the upper end of the chamber 16 axially concentric with the cylindrical valve body 10 is a hub shaped open ended housing 25 which is attached to the valve body 10 by four preferably equally spaced radial arms 26, 27, 28 and 29, as best shown in Figure 2. The valve body 10, hub shaped housing 25 and arms 26, 27, 28, and 29 are preferably formed as an integral casting.

A valve assembly, designated as a whole by the numeral 30, is pendently supported within the valve body 10 from the hub shaped housing 25 by suitable means, such as the bolts 51, shown in Figure 2.

The valve assembly 30 includes a cylindrically shaped valve support 32 axially disposed within the valve body 10 and extending downwardly from the hub shaped housing 25, with which it is in register, through the chambers 16 and 17 into the discharge mouth 18. A removable cover plate 33 forms a closure for the lower end of the cylindrically shaped valve support 32.

Telescopically mounted on the valve support 32 and supported thereon in a manner hereinafter described, is a lower valve 34 arranged to seat upwardly against the lower valve seat 22. Similarly mounted and supported on the valve support 32 is an upper valve 35 arranged to seat upwardly against the upper valve seat 19.

Referring particularly to Figure 4, the lower valve 34 comprises a cylindrical sleeve-like upper portion 36 arranged in telescoping engagement with the valve support 32, a flared skirt portion 37 continuing to an inwardly tapering portion 38 and terminating in a sleeve 39 arranged in telescoping engagement with the valve support 32.

Depending from the lower valve 34 and secured thereto in any practical manner, as by the bolts 40 shown in Figure 1, is a packing retaining ring 41 arranged to receive suitable packing 42. The packing 42 embraces the lower portion of the valve support 32 providing a seal against leakage of pressure and coal dust past the sleeve 39.

The upper valve 35 is generally similar to the lower valve 34. Again referring particularly to Figure 4, the upper valve 35 comprises a cylindrical sleeve-like upper portion 43 arranged in telescoping engagement with the valve support 32, a flared skirt portion 44 continuing to an inwardly tapering portion 45 and terminating in a cylindrical sleeve 46 arranged telescopically to receive the cylindrical portion 36 of the lower valve 34.

Depending from the upper valve 35 and secured thereto in any practical manner, as by the

bolts 47, shown in Figure 1, is a packing retaining ring 48 arranged to receive suitable packing 49. The packing 49 embraces the cylindrical portion 36 of the lower valve 34 providing a seal against leakage of pressure and coal dust from the chamber 17 past the cylindrical valve portion 36.

A packing retaining ring 50 embracing the cylindrical portion 43 of the upper valve 35, is secured in any suitable manner as by the bolts 51, shown in Figure 1, to the annular flange 52 which is formed with and projects outwardly of the upper end of the valve support 32. Suitable packing 53 within the retaining ring provides a seal against leakage of coal dust past the cylindrical valve portion 43.

Upper and lower valves 35 and 34 are operated by hydraulic motors 54 and 55, respectively, disposed one above the other within the valve

support 32. The upper hydraulic motor 54 comprises a cylinder 56 having a piston 57 reciprocable therein and arranged to be actuated in opposite directions by hydraulic fluid. Similarly, the lower hydraulic motor 55 comprises a cylinder 58 having a piston 59 reciprocable therein and arranged to be actuated in opposite directions by hydraulic fluid.

The upper motor cylinder 56 is closed at its upper end by a cylinder head 60 and the lower motor cylinder 58 is closed at its lower end by a cylinder head 61. A cylinder head 62 common to the two hydraulic motors 54 and 55, forms a closure for the adjacent lower and upper ends, respectively, of the upper and lower motor cylinders 56 and 57, respectively. As best shown in Figure 4, the cylinders and cylinder heads may be firmly secured in assembled relation by means of bolts 63 that project through the cylinder head 60, extend along the outside of the cylinder 56 and are threaded at their opposite end into the cylinder head 62; and bolts 64 that project through the cylinder head 61, extend along the outside of the cylinder 58 and are threaded at their opposite end into the cylinder head 62.

The common cylinder head 62 is provided with a flange 65 arranged to seat on an inwardly extending annular flange 66 formed with the valve support 32. Suitable means, such as bolts 67, extend through the flange 65 into the flange 66 to rigidly secure the motors 54 and 55 with the valve support 32.

A piston rod 68 is secured at one end to the piston head 57 of the upper motor 54 and projects therefrom upwardly through the stuffing box 69 of the cylinder head 60, while a piston rod 70 is secured at one end to the piston head 59 of the lower motor 55 and projects therefrom downwardly through the stuffing box 71 of the cylinder head 61.

The upper valve 35 is connected with the free end of the piston rod 68 and the lower valve 34 is connected with the free end of the piston rod 70, by means hereinafter described, whereby reciprocating movement of the piston rods 68 and 70 is transmitted to the valves 35 and 34, respectively. The cylinder heads 60, 61 and 62 are preferably provided with ball check valves 147 to insure quick opening of the valves. An enlarged view of one of the check valves 147 is shown in Figure 7.

The connecting means for the upper valve 35 includes a yoke 72 secured, as at 73 in Figure 4, to the free end of the piston rod 68. Threaded in the free ends of the diametrically opposite

75 downwardly extending arms 74, 75 of yoke 72

are pins 76, 77, respectively, projecting outwardly through diametrically opposite vertically elongated slots 78, 79, respectively, formed in the support 32. The projecting ends of the pins 76, 77 extend into and support the valve member 35. Similarly, a yoke 80 is secured, as at 81, to the free end of piston rod 79, and upturned arms 82, 83 of yoke 80 have pins 84, 85 threaded in their free ends. The pins 84, 85 project through the diametrically opposite vertically elongated slots 86, 87 formed in the support 32 and the projecting ends of the pins 84, 85 extend into and support the valve member 34.

In order to actuate the piston 57 of the upper motor 54, two conduits or pipes 88, 89 are provided which are connected respectively with the upper and lower ends of the motor cylinder 56 through a passage 90 in the upper cylinder head 60 and a passage 91 in the lower cylinder head 62, as best shown in respective Figures 5 and 6, and means is provided to supply fluid under pressure through one of these pipes while allowing fluid to escape from the other pipe and vice versa. Similarly, to actuate the piston 59 of the lower motor 55, two conduits or pipes 92, 93 are provided which are connected respectively with the upper and lower ends of the motor cylinder 52 through a passage 94 in the upper cylinder head 62 and a passage 95 in the lower cylinder head 61, as best shown in respective Figures 5 and 6, and means is provided to supply fluid under pressure through one of these pipes while allowing fluid to escape from the other pipe and vice versa.

The radial arms 26, 27, 28, 29 formed with the valve body 10 are provided respectively with passages 96, 97, 98, 99 through which the respective conduits or pipes 93, 92, 88, 89 extend, as shown in Figure 2, to the fluid reversing means located outside the valve body 10. This means may be any suitable well known type of valve mechanism such as a Vickers cam operated 4-way valve, type C-472-EA. One such valve is shown at 100, which is connected with the pipes 88 and 89 for controlling the flow of fluid to the cylinder 56 of upper motor 54, and another such valve is shown at 101, which is connected with the pipes 92 and 93 for controlling the flow of fluid to the cylinder 58 of lower motor 55, as best shown in Figure 8. The valves 100 and 101 are suitably secured side by side on the outside of the valve body 10. A feed line 145 and a return line 146 connect the distributing valves 100 and 101 with a suitable source of fluid under pressure.

The cams 102 and 103 for operating the valves 100 and 101, respectively, are mounted on a shaft 104 disposed horizontally above the valves 100 and 101. A housing 105 for the cams 102 and 103 is rigidly secured to the valve body 10 and is provided at its ends with bearings 106 and 107 in which the opposite ends of the shaft 104 are journaled. The shaft 104 is operated from a motor 108 through any suitable speed reducing means.

The cams 102 and 103 are constructed and arranged, as will be hereinafter described in greater detail, to effect a certain sequence of events during each revolution of the shaft 104. Starting, for example, with the cam followers 109 and 110 of valves 100 and 101, respectively, in engagement with the high parts of cams 102 and 103, both of the material feed valves 34 and 35 are closed, as shown in Figures 1 and 4. Then, when the cam follower 109 of valve 100 engages the low part of cam 102 while the cam follower 110 of valve 101 is still in engagement with the high part of cam 103, upper feed valve 35 opens

while lower feed valve 34 remains closed, as shown in Figure 5, whereupon the finely divided coal or other material can drop by gravity from chamber 16 into chamber 17. Following this, the cam follower 109 of valve 100 re-engages the high part of cam 102 while the cam follower 110 of valve 101 is still in engagement with the high part of cam 103, whereupon upper feed valve 35 is again closed and lower feed valve 34, of course 10 remains closed. Finally, the cam follower 110 of valve 101 engages the low part of cam 103 while the cam follower 109 of valve 100 is still in engagement with the high part of cam 102, whereupon lower feed valve 34 opens, as shown 15 in Figure 6, and the finely divided coal or other material can drop by gravity from chamber 17 into discharge mouth 18. The cycle is then repeated for each revolution of the shaft 104.

In order to facilitate discharge of coal from 20 the chamber 17 through the discharge mouth 18 and into the pressurized receptacle 12 when the lower feed valve 34 opens, valve controlled means is provided for introducing air under pressure into the chamber 17 above the charge of coal 25 disposed therein. Valve controlled means is also provided for venting or exhausting the pressure trapped in chamber 17 after the coal has been discharged therefrom and the lower feed valve 34 has closed, and before the upper feed valve 30 35 has reopened.

The operation of the valve controlled pressurizing and venting means, just referred to, is synchronized with the operation of feed valves 34 and 35, so that all four of these elements function in a regular sequence for each revolution 35 of the shaft 104, as hereinafter described.

Referring first to the valve controlled pressurizing means, with regard particularly to Figure 9, the valve body 10 is provided in the wall 40 thereof adjacent the ledge 14 with an annular passage 111 that stops short of making a complete circle by the walls 8 and 9, see Figure 3, for a purpose later explained. A plurality of circumferentially spaced jet openings 112 provide communication between the passage 111 and the upper end of chamber 17 whereby air under pressure is admitted in high pressure jets to chamber 17 above the coal therein for facilitating discharge of coal. Pressure is admitted to the passage 111 through the port 113 from the supply pipe 114 which leads from a suitable source of supply (not shown).

A valve 115, interposed between the supply pipe 114 and port 113, controls the delivery of air under pressure to the passage 111, and is disposed immediately above the housing 105 for the cam operating shaft 104, as best shown in Figures 8 and 9. The valve 115 comprises a casing 116, secured in any suitable manner to the valve body 60 10, and has an inlet port 117 communicating with supply pipe 114 and an outlet port 118 communicating with the port 113.

Internally, the valve 115 is provided with a seat 119 for receiving the valve member 120, and 65 a spring 121 normally retains the valve member 120 in its seated or closed position. The valve stem 122 of valve member 120 extends through the lower sleeve portion 123, which forms a guide for the valve stem 122. The lower end of the valve stem 122 projects into the housing 105 and carries a cam follower 124 responsive to a cam 125 mounted on the cam operating shaft 104.

Referring now to the valve controlled venting or exhaust means, with particular attention to 70 Figure 10, the valve body 10 is provided in the

wall thereof adjacent the ledge 14 with a chamber 126, disposed between the walls 8 and 9 that define the ends of the annular passage 111, as best shown in Figure 3. A port 127 provides communication between chamber 126 and the upper end of chamber 17 and a port 128 opens from chamber 126 exteriorly of the valve body 10.

The walls 8 and 9 closing off the chamber 126 from the annular passage 111, prevent the high pressure air from escaping into chamber 17 through the large port 127 and insure a jet action of the air through the jet openings 112.

A vent valve 129, controlling the exhaust of air pressure from the chamber 17 is disposed immediately above the housing 105 for the cam operating shaft 104, as best shown in Figures 8 and 10. The valve 129 comprises a casing 130, secured in any suitable manner to the valve body 10, and has a discharge port 131 communicating with a vent pipe 132 and an intake port 133 communicating with the port 128.

Internally, the valve 129 is provided with a seat 134 for receiving the valve member 135, and a spring 136 normally retains the valve member 135 in its seated or closed position. The valve stem 137 of valve member 135 extends through the lower sleeve portion 138, which forms a guide for the valve stem 137. The lower end of the valve stem 137 projects into the housing 105 and carries a cam follower 139 responsive to a cam 140 mounted on the cam operating shaft 104.

The timing and order of operation of the coal feed valves 34, 35, the pressurizing valve 115 and the exhaust valve 129 is determined by the shape and position of the cams 102, 103, 125 and 140 around the cam shaft 104. Figure 11 is a diagrammatic representation of the cams 102, 103, 125 and 140, with their respective cam shoulders 141, 142, 143 and 144 shown in their proper relation for controlling the operation of the valves 34, 35, 115 and 129. With the cams 102, 103, 125 and 140 as shown in Figure 11, both feed valves 34 and 35 are closed as in Figure 1, the pressurizing valve 115 is closed as in Figure 9, and the vent valve 129 is closed as in Figure 10.

With the cam shaft 104 rotating in the direction indicated by the arrows a sequential operation of the feed valves, pressurizing valve and vent valve occurs during each revolution of the shaft. First the cam shoulder 144 of cam 140 engages cam follower 139 and effects opening of the vent valve 129, then cam shoulder 141 of cam 102 disengages cam follower 109 and effects operation of distributing valve 100 to a position providing for passage of pressure fluid through pipe 88 to the upper end of the cylinder 58 of hydraulic motor 55, whereby upper feed valve 35 is opened. Both feed valve 35 and vent valve 129 remain open for an interval, during which coal drops by gravity into chamber 17 and the air displaced thereby is consequently permitted to freely exhaust through vent valve 129.

Upon continued rotation of cam shaft 104, cam shoulder 144 of cam 140 disengages cam follower 139 whereupon the spring 136 closes the vent valve 129. Following this, cam shoulder 141 of cam 102 engages cam follower 109 and effects operation of distributing valve 100 to a position whereby pressure fluid is admitted through pipe 89 beneath the piston 57 of hydraulic motor 54 and pressure fluid above the piston 57 is vented through pipe 88, whereupon upper feed valve 35 closes.

An interval later cam shoulder 143 of cam 125 engages cam follower 124 and effects opening of pressurizing valve 115 whereby fluid under pressure as high or preferably higher than the pressure in the tank or receptacle 12 is admitted to chamber 17 through the jet openings 112. Thereafter, cam shoulder 142 of cam 103 disengages cam follower 110 and effects operation of distributing valve 101 to a position providing for passage of pressure fluid through pipe 92 to the upper end of the cylinder 58 of hydraulic motor 55, whereby lower feed valve 34 is opened. Both feed valve 34 and pressurizing valve 115 remain open for an interval, during which coal drops from chamber 17 into receptacle 12. Since the pressure on the head of coal in chamber 17 is at least equal to the pressure in receptacle 12, the coal freely empties from the chamber 17, and the jets of pressure fluid issuing from the jet openings 112 further facilitate discharge of coal from the chamber 17.

Upon further rotation of cam shaft 104, cam shoulder 143 of cam 125 disengages cam follower 124 whereupon spring 121 closes the pressurizing valve 115. Following this, cam shoulder 142 of cam 103 engages cam follower 110 and effects operation of distributing valve 101 to a position whereby pressure fluid is admitted through pipe 93 beneath piston 59 of hydraulic motor 55 and pressure fluid above the piston 59 is vented through pipe 92, whereupon lower feed valve 34 closes.

The above cycle of operations is repeated for each revolution of the cam shaft 104. The cams 102, 103, 125 and 140 may be modified to alter the timing of the valves, however, at all times the lower feed valve 34 should be fully closed before the upper feed valve 35 opens; the upper feed valve 35 should be fully closed before the lower feed valve 34 opens; the pressurizing valve 115 should be fully closed before upper feed valve 35 opens; and vent valve 129 should be fully closed while lower feed valve 34 is open.

I claim:

1. In a material feeding device, a body providing a pressure chamber between two valve seats, a valve support extending lengthwise through said chamber forming between the periphery of said support and said valve seats an annular inlet to the said chamber and an annular outlet from the said chamber, an annular inlet valve extending about said support movable lengthwise therealong and cooperating with one of said seats to control said annular inlet, an annular outlet valve extending about said support movable lengthwise therealong and cooperating with the other of said valve seats to control said annular outlet, valve operating means within said valve support for actuating said valves, said valve support being open at its lower end providing access to said operating means without disassembling said valves, and a removable cover for said opening.

2. In a material feeding device, a body providing a pressure chamber between two valve seats, an inlet valve movable lengthwise to the chamber and cooperating with one of said valve seats to control the inlet to said chamber, an outlet valve movable lengthwise to the chamber and cooperating with the other of said valve seats to control the outlet from said chamber, a valve support lengthwise to the chamber, valve operating means within said valve support including pressure fluid cylinders disposed one above the other and a common cylinder head for the adja-

cent ends of said cylinders, and means rigidly securing said cylinder head with said valve support for supporting said valve operating means within said valve support.

3. In a material feeding device, a body providing a pressure chamber between two valve seats, an inlet feed valve cooperating with one of said valve seats to control the inlet to said chamber, an outlet feed valve cooperating with the other of said valve seats to control the outlet from said chamber, a valve support in said chamber movably supporting said inlet and outlet feed valves, pressure fluid operated motors in said valve support for actuating said inlet feed valve and outlet feed valves, a pair of pressure fluid distributing valves outside said body for controlling the operation of said motors, means including a valve connecting said chamber with a source of pressure, means including a valve for venting said chamber, a rotatable shaft outside said body, and a plurality of cams on said shaft arranged

5 10 15

to successively contact the stems of said distributing valves, pressurizing valve and vent valve for sequential operation thereof.

4. A construction according to claim 3, in which the cams are arranged about said cam shaft to effect for each revolution thereof sequential operation as follows, opening of said vent valve, opening of said inlet feed valve, closing of said vent valve, closing of said inlet feed valve, opening of said pressurizing valve, opening of said outlet feed valve, closing of said pressurizing valve and closing of said outlet feed valve.
